(57) **CLAIM**

The ornamental design for a battery rod for an electronic cigarette, as shown and described.

DESCRIPTION

FIG. 1 is top-rear perspective view of a battery rod for an electronic cigarette, showing my design;

FIG. 2 is a front view thereof;

FIG. 3 is a right side view thereof;

FIG. 4 is a left side view thereof;

FIG. 5 is a rear view thereof;

FIG. 6 is a top view thereof;

FIG. 7 is a bottom view thereof; and,

FIG. 8 is a cross-sectional view thereof, taken along Line 8-8 of FIG. 2.

The broken lines in the drawings depict portions of the battery rod for electronic cigarette that form no part of the claimed design.
